Primary Examiner — Steven J Czyz(74) *Attorney, Agent, or Firm* — Wolf, Greenfield & Sacks, P.C.(57) **CLAIM**

The ornamental design for an exit device with status indicator, as shown and described.

DESCRIPTION

FIG. 1 is a top, front, left side perspective view of an exit device with status indicator;

FIG. 2 is a top, front, right side perspective view of FIG. 1; FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1; and,

FIG. 8 is a bottom plan view of FIG. 1.

The evenly spaced broken lines depict portions of the article that form no part of the claimed design; the dash-dot-dash lines represent the boundary of the claimed design and forms no part thereof.
